UNITED STATES PATENT OFFICE

2,208,388

OIL TOOL SPINNER

Guy R. Pothe, Fullerton, Calif.

Application December 11, 1939, Serial No. 308,630

20 Claims.

(Cl. 255—1)

This invention relates to oil drilling rigs and has particular reference to a device for facilitating connecting and disconnecting drilling tools, couplings and pipes used in oil drilling.

5 Machinery used in connection with oil drilling has been so perfected and standardized, and the methods of handling the various drilling tools and connections thereof are so well known that no explanation is here required, except to mention that the rotary table of such rig is a rather elaborate metallic device centrally shaped to receive a master bushing which, in turn, is recessed to receive a Kelly bushing, both of which devices are commonly employed and well known in the 10 art.

The object of the present invention is to provide a device which is interchangeable with such Kelly bushing and which is fitted with a turn table on which to receive and support the end of 15 a tool, coupling or the like, to facilitate connection and disconnection thereof. A further object is to provide means on such table for guiding the end of such part resting thereon.

It is customary in present day practice to throw 20 a wooden plank on the metallic table, on which to support such tool or coupling and so as not to damage the contacting edges of the part while spinning it around in connecting or disconnection. In view of this, it is a further object of the 25 invention to provide a covering for the device of the invention of such nature that it will support the end of the part resting thereon without damage thereto.

The further objects and the various advantageous features of the invention will be readily appreciated from the following description, especially when read in connection with the appended drawings, of which:

Fig. 1 is a plan view of the rotary table of a 30 drill rig of any commercially well known construction, showing the device of the invention seated therein;

Fig. 2 is a cross sectional side elevation of the center portion of Fig. 1, on a larger scale and 35 taken substantially through the center thereof;

Fig. 3 is also a cross sectional side elevation of the center portion of Fig. 1, and it includes an additional feature not shown in the foregoing; and

40 Figs. 4, 5 and 6 are fragmentary side elevations, partly in section, of the upper portion of the device of the invention and exhibiting further modifications the importance of which will be described presently.

45 This application is a continuation in part of

application, Ser. No. 283,557, filed by me on July 10, 1939.

The numeral 1 denotes the rotary table of any commercially well known type and which is centrally recessed to receive the usual master bushing 2. The latter, in turn, is centrally perforated at 3 to receive the Kelly bushing which guides the drilling tool, in operation. No further reference is made to this Kelly bushing, and it is not illustrated, having been lifted out of the master bushing to make room for the structure of the invention. The latter is shown to comprise a base 10, into which a central stud 11 is fitted, and this stud serves as a pivot upon which a disc 12 is seated to rotate. Suitable ball or roller bearings 13 are provided between the disc and the base to take the end thrust against the disc when the weight of a heavy object is imposed thereon. In order to remove the device from the rotary table with ease, it is advantageous to provide on the base 10 suitable hand grips 14.

In operation, a tool, pipe or coupling is set on end on the disc 12, and it is important to note that the top of this disc is shown covered with a thick, preferably resilient lining 15, provided for the purpose of protecting the end of the part resting thereon from damage when the part, together with the disc in the usual manner is spun around at high speed to effect connection and disconnection of the parts thereabove. Because the end of the part resting on the disc becomes somewhat imbedded in this lining, it is seen that an additional function of the lining is to check the tendency of the part resting thereon to slide off the disc when so rotated.

Referring now to Fig. 3, it is noted that, while the base 10 and the disc 12 may remain as described, the lining 15, of the latter, is shown centrally perforated to receive a pilot 16, rising from the stud 17. The lower end of this stud may remain exactly like stud 11 of Fig. 1. This pilot serves as a pivot upon which to guide the end of the drill part seated on the disc and thereby to prevent it from sliding off the spinning disc in case the resilient lining is insufficient to maintain the part in position.

At times, while the Kelly bushing is in position, it is required to mount or dismount some part, such as a coupling or pipe section. To facilitate such operation, the common method is to drive a spike or other handy element into the derrick flooring to guide the end of such part, but this is a very crude method partly because, when the parts are rapidly spun around as required in order to perform the operation, the end of the

contacting part chews up the flooring. This may be prevented by raising the parts slightly above the flooring, and attempting manually to guide the parts, an expedient which, however, merely makes the operation more difficult and increases the labor cost.

In such case, the device of the invention may be placed on the flooring adjacent to the rotary table and the parts to be connected or disconnected rested directly thereon. It is customary to wind a rope, from a capstan on the floor, around the part and to pull this rope away quickly to cause the part to spin around at high speed, an operation to which my device is ideally suited. 15 And because the device facilitates such spinning operation, I have named the invention an oil tool spinner.

In order to prevent the device from slipping on the usually greasy derrick floor during such spinning operation, I have provided a series of perforations 20 in the base 10, through which nails may be hammered into the flooring. A more permanent method, however, is to place pointed studs 21 in these perforations, as indicated in 25 the drawings. This will also save the flooring.

In cases where the part to be seated on the device of the invention has a much larger opening than the stud 16 and centering for this reason is found difficult, it may be found advisable 30 to fit a cap 22 over the stud, substantially as indicated in Fig. 4, the top surface of which is suitably cone-shaped. This cap should also be made from softer, preferably resilient material in order that it may serve the double purpose of 35 better retaining the part in position while at the same time protecting it from damage.

A combination of the foregoing advantageous features is illustrated in Fig. 5, where the disc 25 is shown cone-shaped; the pilot 26 rises clear 40 of this disc; and the lining 27 offers protection for the part which is seated on the cone and guided by the pilot.

Frequently, it is required to handle large facinating tools and the like, and the disc ordinarily 45 used may not be large enough for this purpose unless the rotary table is large enough to hold an oversize master bushing. In such cases, it may be necessary to increase the diameter of the disc at the top, substantially as indicated in 50 Fig. 6, where the disc 30 is shown made with a much larger top flange 31. With this large flange added, it may be difficult to find room for the handles 14, and it may be preferable to provide indentations in the underside of the flange to 55 serve as hand grips. Such indentations are indicated at 32.

The disc is, in this case also, covered by a resilient lining 33, for the purposes specified, and it may be recessed to fit over the pilot 16 60 of Fig. 3, or the disc 15, of Fig. 2 may be modified as shown in Fig. 6 to obtain similar results on a disc not fitted with a pilot.

Other modifications, within the scope of the appended claims, may be incorporated in order 65 better to carry into practice the principles of the invention, as above outlined.

I claim:

1. A tool spinner for an oil rig rotary table having a central opening for a Kelly bushing, comprising, a base seatable in and closing said opening, and a disc rotatable on said base for supporting the end of an oil tool or the like. 70

2. A tool spinner of an oil rig rotary table having a central opening for a Kelly bushing, comprising, a base seatable in and closing said 75

opening, a stud centrally seated in said base, and a disc rotatable on said stud.

3. A tool spinner for an oil rig rotary table having a central opening for a Kelly bushing, comprising, a base seatable in and closing said opening, a stud centrally seated in said base, a disc rotatable on said stud, and antifriction bearings between said disc and base. 5

4. A tool spinner for an oil rig rotary table having a central opening for a Kelly bushing, 10 comprising, a base seatable in and closing said opening, a rotary disc centrally seated in said base, and antifriction bearings between said disc and the said base.

5. A tool spinner for an oil rig rotary table 15 having a central opening for a Kelly bushing, comprising, a base seated in and closing said opening, a disc mounted for rotation on said base, and means on said disc for guiding a drill tool or the like placed thereon. 20

6. A tool spinner for an oil rig rotary table having a central opening for a Kelly bushing, comprising, a base seatable in and closing said opening, a disc rotatable on said base for supporting the end of an oil tool or the like, and a thick resilient pad covering the top of said disc. 25

7. A tool spinner for an oil rig rotary table having a central opening for a Kelly bushing, comprising, a base seatable in and closing said opening, a stud centrally seated in said base, a disc rotatable on said stud, and a thick resilient pad covering the top of said disc. 30

8. A tool spinner for an oil rig table having a central opening for a Kelly bushing, comprising, a base seatable in and closing said opening, 35 a stud centrally seated in said base, a disc rotatable on said stud, a thick resilient pad covering the top of said disc, and antifriction bearings between said disc and the said base.

9. A tool spinner for an oil rig rotary table 40 having a central opening for a Kelly bushing, comprising, a base seatable in and closing said opening, a rotary disc centrally seated in said base, a resilient pad covering the top of said disc, and antifriction bearings between the table and 45 disc.

10. A tool spinner for an oil rig rotary table having a central opening for a Kelly bushing, comprising, a base seatable in and closing said opening, a disc mounted for rotation on said 50 base, a resilient pad covering the top of the disc, and means on said disc for guiding a drill tool or the like placed on end thereon.

11. A tool spinner for an oil rig rotary table comprising, a base seatable in said table, a disc 55 rotatable on said base, and a centering stud rising from said disc.

12. A tool spinner for an oil rig rotary table comprising, a base seatable in said table, a pivot rising from said base, a disc rotatable on said 60 pivot, and a centering stud rising from said pivot.

13. A tool spinner for a rotary oil rig comprising, a base seatable in the rotary table of the rig, said base being made with bottom projections for steadyng the device when set for use 65 on the flooring of the rig, a disc rotatable on said base, and centering means rising from said disc.

14. A tool spinner for a rotary oil rig comprising, a base seatable in the rotary table of the rig, said base being made with bottom projections for steadyng the device when set for use 70 on the flooring of the rig, a disc rotatable on said base, and thrust bearings between said disc 75

and base, and centering means rising from said disc.

15. A tool spinner for the rotary table of an oil rig, comprising, a base seatable in said table, 5 a disc rotatable on said base, a centering stud rising from said disc, and a cone-shaped centering cap seatable on said stud to cover the top of said disc.

16. An oil tool spinner for a rotary drilling 10 table comprising, a base seatable in said table, and a disc rotatable on said base, said disc having a cone-shaped top surface.

17. An oil tool spinner for a rotary drilling table comprising, a base seatable in said table, 15 and a disc rotatable on said base, said disc having a cone-shaped top surface terminating in a centering stud.

18. An oil tool spinner for a rotary drilling table having a central opening for a Kelly bush-

ing, comprising, a base seatable in and closing said opening, a disc rotatable on said base, the top of said disc being made with a large flange to accommodate large facing tools and the like, and a thick resilient pad covering the top surface of said flange.

19. A tool spinner for an oil rig rotary table comprising, a base seatable in said table, a disc rotatable on said base, said disc having a larger top flange, a thick resilient pad on top of said disc, and centering means rising from the disc through said pad.

20. An oil tool spinner for a rotary drilling table comprising, a base seatable in said table, a disc rotatable on said base, said disc having a cone-shaped top surface, and a resilient pad covering said cone.
